United States Patent Office.

ANDREW PARKER, OF NEW YORK, N. Y.

Letters Patent No. 80,208, dated July 21, 1868.

IMPROVED BUREAU-BEDSTEAD.

The Schedule referred to in these Letters Patent and making part of the same.

TO ALL WHOM IT MAY CONCERN:

Be it known that I, ANDREW PARKER, of the city, county, and State of New York, have invented a new and improved Bureau-Bedstead; and I do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a plan or top view thereof.

Figure 3 is a sectional side elevation thereof when folded up to resemble a bureau.

Similar letters indicate corresponding parts.

This invention relates to a bureau-bedstead, which, when drawn out, assumes the form and shape of a regular bedstead, so that the same can be used precisely in the same manner as a bedstead, and at the same time it can be folded up and brought in a comparatively small compass, whenever it may be desired.

The invention consists in the arrangement of a flap, which is hinged to the head-piece of the bedstead, and provided with V-shaped grooves in its under surface, so that the same, when folded down, will catch over V-shaped projections on the foot-piece and retain the same firmly in position.

The head and foot-pieces are provided with check-pieces, the upper edges of which are hollowed out, so that when the bedstead is folded up, two semicircular cavities are formed, which are filled up by side wings hinged to the ends of the flap on the head-piece.

Between the head and the foot-pieces is the slatted frame, which is made in two parts, connected to each other and to the head and foot-pieces by hinges, so that the same can be folded up or extended, as may be required.

A represents the head-piece of my bureau-bedstead, which is provided with a hinged flap, B. The space above this flap may be occupied by a looking-glass, or it may be ornamented in any suitable manner, and from the top edge of the head-piece project two lips, a, which catch over the edge of the flap, when the same is turned up to the position shown in fig. 1, and retain it in position.

The head-piece A connects with the foot-piece C by a slatted frame, D, which is composed of two parts, united to each other and to the head and foot-pieces by hinge-joints, in such a manner that the same can be folded up to the position shown in fig. 3, or unfolded to the position shown in fig. 1.

When the bedstead is unfolded, the head-piece A may be steadied by a leg secured to it in any suitable position.

When the frame D is folded, the check-pieces *b* of the foot-piece C come close up to check-pieces *b* of the head-piece, and by turning down the flap B, to the position shown in fig. 3, the frame is completely enclosed, and the furniture assumes the appearance of a bureau, leaving room enough between the folded frame and the head and foot-pieces for the mattress and bed-clothes.

The flap B is provided at its under surface with V-shaped grooves, *d*, which, when said flap is turned down, catch over corresponding V-shaped projections *e* on the foot-piece, and retain the same firmly in position.

The check-pieces *b* *c* of the head and foot-pieces are hollowed out at their upper edges, so that, when the frame D is unfolded, the furniture will assume the shape of a regular bedstead, and when said frame is folded up, and the head and foot-pieces are brought together, cavities *f* are formed, which are closed up by side wings *g* hinged to the flap B.

When the frame D is unfolded, the side wings *g* are folded in to the position shown in figs. 1 and 2, so that they are out of the way.

By these means a piece of furniture is obtained, which, when unfolded, has the precise appearance of a common bedstead, and which can be readily folded up and brought in the form of a bureau.

Having thus described my invention, what I claim as new, and desire to secure by Letters Patent, is—

A bureau-bedstead, composed of a head-piece, A, and foot-piece C, united by a hinged frame, D, and provided with a hinged flap, B, which, when folded up, is retained by lips *a* on the head-piece, and which, when folded down, catches over V-shaped projections *e* on the foot-piece, as shown and described.

ANDREW PARKER.
